VACUUM CAN

William Miles Ryan and John W. Bold, Brooklyn,
N. Y., assignors to Ryan Coffee Corporation,
New York, N. Y., a corporation of New York

Application February 8, 1933, Serial No. 655,732

8 Claims. (Cl. 220—54)

This invention relates to cans provided with interior collars, as commonly used in vacuum sealed cans, and has particular reference to improvements in the body and collar structure of such cans and method of making, as will hereafter appear.

Heretofore, cans with collars have been formed by beading the collar within the can body after the collar and can body have been formed separately. This method of construction results only in a non-rigid and easily removable can collar which is undesirable because it is not air tight and which consequently is unsuitable for packing liquids. When such can collars are loosened and displaced from their position, even solid contents are spilled and sharp can edges are thereafter exposed which endanger users. Furthermore, once the collar is removed it becomes useless because its seat has been lost.

Our invention relates to a new method of constructing cans with collars which will permit the collar to remain entirely rigid and which furnishes an air and liquid tight receptacle even after the outside seal on the can is broken and the cover removed.

In the accompanying drawings,

Fig. 1 is an elevation of a can embodying the invention partly in section;

Fig. 2 is a section on the line 2—2 of Fig. 1;

Fig. 3 is a section on the line 3—3 of Fig. 1;

Fig. 4 is a section on the line 4—4 of Fig. 1;

Fig. 5 is a view similar to Fig. 1 with the top removed and showing a slight modification;

Fig. 6 is a perspective view showing the process of opening the finished can;

Fig. 7 is a detail view of the collar as showing in the can after being opened;

Fig. 8 is a plan view showing the combined collar and top blank provided with the opening scores and ready to be folded;

Fig. 9 is a plan view partly in section, showing the collar and top blank partly folded;

Fig. 10 is a similar view showing it further folded;

Fig. 11 is a plan view of the bottom body blank;

Fig. 12 shows the bottom body blank partly folded;

Fig. 13 shows the top body and collar and bottom body seamed together in the flap ready for joining and soldering; and

Figs. 14 and 15 are details showing the body ends.

Referring to the drawings, in Figs. 1, 11 and 12, 1 is the lower body blank notched out at the

corners as shown and which is rolled over on the top edge as at 3 and the end edges as at 5, 6 for lock seaming to each other when the collar has been attached.

Referring to Figs. 1, 8, 9 and 10, 8 is the combined body top and collar blank whose lower crimped edge 9 is to become the top edge of the collar when folded over along intermediate folding line 10 which forms the edge 11 shown in Figs. 9 and 10, Fig. 10 showing the edge 11 curled over to receive and be lock-seamed with curved edge 3 of body section 1, as in Fig. 12. Blank 8 is also scored for tearing in the usual manner by scores 13, and providing the tearing tongue 14.

After the foregoing operations are completed, the two parts are lock-seamed together preferably to form the interior bead or seam 15 which leaves the outer surface smooth to effectively receive a paper label, which is an advantage over the usual type of vacuum sealed can where the collar is rolled into the body and provides an objectionable exterior bead which precludes satisfactory application of a paper label, thereby requiring more expensive lithographing of the outside. If, however, it is desired to have the circumferential seam 15 outside, it is simply necessary to make the bends 11 and 3 the other way, or any other suitable rearrangement can be made to provide an external bead or seam 15. This construction as thus far described has a marked advantage over the ordinary construction above described in that this invention provides a circumferential seam of much increased stiffness as compared with the prior construction, and thereby the can of this invention will have greater resistance to deformation or fracture.

After producing the assembled flat as shown in Fig. 13, the flat is bent up and joined as shown in Fig. 14 in the usual manner of making side seams by locking and soldering as at 16 in Fig. 4, it being observed that the blanks are so cut as to cause the ends of seam 15 to butt as seen in Fig. 3. A simple overlap and soldering is sufficient for the collar as shown at 17 in Figs. 2 and 7.

This provides a cylindrical can body which is ready for flanging and attaching the top and bottom heads in the usual manner. The crimped collar edge 9 gives a sufficiently reduced or tapering collar as to facilitate removal of the cover.

In Fig. 5 a slight modification is shown wherein the top body section 18 is made separate from the collar 19, but are equally tight when joined together and seamed and soldered as shown.

By this can structure, a great advantage over present cans with collars is gained by reason of the fact that the can collar is rigidly attached to the can body, and will hold liquids as well as solids whereas, present can collars are not air tight after the can is opened, and are all too easily removed, causing losses of contents and exposure of sharp edges which endanger users. This can will tightly hold liquids as well as solids up to the top of the collar even after the outer seal is broken and the cover has been removed; the collar being always rigidly and permanently attached to the body. A further advantage is that the circumferential seam strengthens the can against crushing, or if crushed, will not loosen the collar as has heretofore happened.

The invention claimed is:

1. A sheet metal container comprising a lower cylindrical wall, a double collar joined at its lower end to said wall in a lock seam, the vertical edges of said wall and of the outer collar being joined in a continuous lock seam outside of said seam joining said double collar to said wall.
2. A sheet metal container comprising a lower cylindrical wall, a double collar joined at its lower end to said wall in a lock seam, the vertical edges of said wall and the outer collar being joined in a continuous lock seam outside of said seam joining said double collar to said wall and the vertical edges of said inner collar overlapping and being soldered together.
3. A sheet metal container comprising a lower cylindrical wall, a double collar joined at its lower end to said wall in a lock seam, the vertical edges of said wall and the outer collar being joined in a continuous lock seam outside of said seam joining said double collar to said wall and the vertical edges of said inner collar overlapping and being soldered together and a cover sealed to the upper edge of said outer collar in a lock seam.
4. A sheet metal container comprising a lower cylindrical wall, a double collar joined at its lower end to said wall in a lock seam, the vertical edges

of said wall and the outer collar being joined in a continuous lock seam outside of said seam joining said double collar to said wall and the vertical edges of said inner collar overlapping and being soldered together and a scoring and a tearing tongue in said outer collar below the upper edge of said inner collar.

5. A sheet metal container comprising a lower cylindrical wall and a double collar joined at its lower end to said wall in a lock seam, the vertical edges of said wall and of the outer collar being joined in a continuous lock seam.

6. A metal can comprising a lower body section and an upper double collar, said double collar comprising an inner wall and an outer wall secured to the top edge of the lower body section in a joint seam, said outer wall having a tearing tongue and a scoring, said lower body section and said outer wall being closed on a vertical seam at right angles to said joint seam.

7. A metal can comprising a lower body section and an upper double collar, said upper double collar comprising a sheet of metal folded double to form an inner wall and an outer wall, said double collar being joined at its fold with the upper edge of said lower section in a joint seam, a tearing tongue and scoring on said outer wall, said inner wall extending above the scoring on the outer wall, and said outer wall and said lower section being closed on a seam at right angles to said joint seam.

8. A metal can comprising a lower body section and an upper double collar, said double collar comprising an inner wall and an outer wall secured to the top edge of the lower body section in a joint seam, said outer wall having a tearing tongue and a scoring, said lower body section and said outer wall being closed on a vertical seam at right angles to said joint seam, and a cover sealed to the top edge of said outer wall.
